(57) **CLAIM**

I claim the ornamental design for a door hinge plate locator, as shown and described.

DESCRIPTION

FIG. 1 is a top, front perspective view of a door hinge plate locator showing my new design;

FIG. 2 is a bottom, front perspective view thereof;

FIG. 3 is a top plan view thereof;

FIG. 4 is a bottom plan view thereof;

FIG. 5 is a side elevation view thereof;

FIG. 6 is an opposite side elevation view thereof;

FIG. 7 is a front elevation view thereof; and,

FIG. 8 is a rear elevation view thereof.

The broken lines in the drawings represent portions of the door hinge plate locator that form no part of the claimed design.
